UNITED STATES PATENT OFFICE.

VINTON E. SISSON, OF CHICAGO, ILLINOIS, ASSIGNOR TO WALTER P. MURPHY, OF CHICAGO, ILLINOIS.

METAL END STRUCTURE FOR FREIGHT CARS.

Application filed October 1, 1920. Serial No. 414,055.

To all whom it may concern:

Be it known that I, VINTON E. SISSON, a citizen of the United States, residing at Chicago, in the county of Cook and State of Illinois, have invented new and useful Improvements in Metal End Structures for Freight Cars, of which the following is a specification.

This invention relates to improvements in end structures for railway cars and more particularly to sheet metal ends for freight cars.

The end of a freight car is subject to very severe shocks and stresses on account of the tendency of the cargo to shift when the train starts and stops and in switching and also to the tendency of the superstructure of the car to weave while the train is in motion. To strengthen this type of car, ends have been constructed of one or more sheets or panels of metal, usually steel, which sheets or panels are formed with corrugations for rigidifying the structure to more readily meet impacts from without, cargo thrusts from within, and the racking strains from weaving.

It is the object of this invention to provide an end of the sheet metal type which is adaptable to either wooden car frames or all metal freight cars and that may be employed for strengthening gondola cars, box cars, or other similar cars. It is a further object of this invention to provide the sheets or panels of the end with corrugations of particular contour that from their form and length are peculiarly adapted to meet the stresses and strains already described. While the corrugations are preferably formed parallel, their relation to each other or their direction is immaterial, likewise the corrugations may be all pressed from one side of the sheet of metal or may be formed from opposite sides, as desired.

While the preferred form of this invention is illustrated upon the accompanying sheets of drawings, yet it is to be understood that minor detail changes may be made without departing from the scope thereof.

In the drawing;

Figure 1 is a view in end elevation of a box car illustrating an embodiment of this invention.

Figure 2 is a view in horizontal section

through the end taken on the line 2—2 of Figure 1, illustrating the attachment of the end to a car having a wooden frame.

Figure 3 is a view similar to Figure 2 illustrating the attachment of the end to an all metal box car.

Figure 4 is an enlarged detail view in vertical section taken on the line 4—4 of Figure 1.

Figure 5 is an enlarged detail view of a fragment of the corner of an end sheet or panel.

Figure 6 is an enlarged detail sectional view taken on the line 6—6 of Figure 5, looking in the direction of the arrows, with the parts beyond the line shown partly in perspective and partly in section.

The box car end, as illustrated, comprises two or more sheets or panels 1, preferably of pressed steel, which are attached to the corner posts, end plate and end sill in the usual manner. Figure 2 illustrates a means of attaching the panels to the wooden corner posts 2 by flanging ends of the panels and securing the flanges to the posts, while Figure 3 illustrates the attachment to an all metal car in which the corner posts 3 are usually in the form of angle irons which secure the end in the manner shown.

A plurality of parallel strengthening corrugations are formed in each panel 1 and merged at their ends into the plane of the panel so that the panel has a flat marginal portion about its edges.

The sectional view of Figure 4 shows the particular construction of the corrugations comprising flat main walls 4 substantially at right angles to the plane of the panel, connected by supplemental walls 5 parallel to the plane of the panel which might be said to be corrugated as they merge at each end into the adjacent ends of the main walls on the arcs of circles of equal radii which are tangential to the main walls and the central portion is depressed on the arc of a circle presenting a concave surface the ends of which are tangential to the end arcs forming a reverse curve therewith. The neutral axis of a corrugated panel, such as illustrated in Fig. 4, lies between the extremities of supplemental walls 5—5. In my construction the main walls 4 are spaced equal distances apart and the supplemental walls 5 all have the same configuration so that the

- neutral axis lies exactly midway between the extremities of supplemental walls 5. This is a material advantage when the panel is made of iron or steel because these metals are equal in tensile and compressive strength, therefore, a panel having its neutral axis in its geometrical center produces a balanced beam and gives the maximum strength for the minimum amount of material. The corrugations are continuous and extend alternately from opposite sides of the neutral axis of the panel, with the supplemental walls of greater width, in cross section, than the width of the main walls.
- 15 A wooden end lining 6 is preferably provided on the inner side of the end and a plurality of filler blocks 7 are received within and attached to a number of the corrugations, as shown, to which the wooden lining is nailed. The width of each corrugation is preferably constant throughout its length and the depth also preferably remains constant throughout the greater part but gradually diminishes at each end until the corrugation merges into the plane of the panel, as shown in Figures 5 and 6.

In theory, the ideal form of corrugation for this purpose would have flat main walls extending at right angles to the plane of the panel as having the greatest strength to resist the stresses imposed on car ends. In practice, in pressing corrugations from a panel by dies, it is very difficult to form the main walls in this relation. In the corrugation illustrated, from its peculiar contour, it is possible to form the main walls 4 substantially at right angles to the plane of the panel. The majority of impacts received by the end of a car are from within and are caused by shifting of the cargo. The cargo thrusts are first received on the wooden lining 6 of the end and as this lining is continuous and is in contact with the supplemental walls of the corrugations, the thrusts will be transmitted from the lining 6 through the end curved portions of the reversely curved concave supplemental walls 5 and distributed through the main walls 4 which, as above said, are most advantageously arranged to meet such stresses.

Furthermore, should a panel in which the corrugations are formed with flat main and supplemental walls substantially at right angles to each other receive a sudden impact of great force, such as often occurs in a shift of cargo, the panel will bend outward in the direction of the blow on account of the resiliency or spring action of the bend at the jointure of the main and supplemental walls and will remain substantially in the bulged position. In the corrugations formed with the concave or reversely curved supplemental walls, as contemplated in this invention, there will be greater resilience between the walls so that the panel as a whole

will be more resilient and can give more without breaking than the other form and having bulged on account of a blow will more readily and more nearly return to its normal plane.

What I claim is:

1. A metal panel for car ends having a plurality of corrugations therein formed with the main walls substantially flat and at right angles to the plane of the panel and with concaved supplemental walls. 70
2. A metal panel for car ends having a plurality of corrugations formed therein, with the main walls of the corrugations formed substantially at right angles to the plane of the panel, and having compound curved portions connecting said walls. 75
3. A metal panel for car ends having a plurality of corrugations of constant width throughout their length formed therein, said corrugations having main walls formed substantially at right angles to the plane of the panel and concave supplemental walls connected by curved portions to the main walls. 80
4. A metal panel for car ends having a plurality of corrugations of constant width throughout their length formed therein, said corrugations having main walls formed substantially at right angles to the plane of the panel, concave supplemental walls, and curved tangential portions connecting said main and supplemental walls. 85
5. A metal panel for car ends having a plurality of corrugations of constant width throughout their length and merged into the panel at the ends with the main walls of the corrugations formed substantially at right angles to the plane of the panel and concave supplemental walls of greater length than the main walls. 90
6. A metal panel for car ends having a plurality of corrugations formed on alternate sides of the neutral axis of the panel and having flat main walls formed substantially at right angles to the plane of the panel connected by compound curved supplemental walls, the end curves of which are tangent to the main walls. 95
7. A metal panel for car ends having a plurality of corrugations formed on alternate sides of the neutral axis of the panel and having main walls formed substantially flat and at right angles to the plane of the panel, and having reversely curved portions connecting said walls, the width of the corrugations exceeding the depth. 100
8. A metal panel for car ends comprising a plurality of walls spaced equal distances apart and positioned substantially perpendicular to the plane of the panel, said walls connected by concaved supplemental walls. 105
9. A metal panel for car ends comprising a plurality of walls spaced equal distances apart and positioned substantially perpendicular to the plane of the panel, said walls 110
- 120
- 125
- 130

connected by concaved supplemental walls, said walls decreasing in width so that said supplemental walls merge into the panel.

10. A metal panel for car ends comprising a plurality of walls positioned substantially vertically to the plane of the panel and spaced equal distances apart, said walls connected by compound curved portions,

5 11. A metal panel for car ends comprising

ing a plurality of walls positioned substantially vertically to the plane of the panel and spaced equal distances apart, said walls connected by compound curved portions, said walls decreasing in width so that said compound curved portions merge into the 15 panel.

VINTON E. SISSON.
